UNITED STATES PATENT OFFICE.

J. WALTER FLAGG, OF WORCESTER, MASSACHUSETTS.

AUTOMATIC CASH-CARRIER.

SPECIFICATION forming part of Letters Patent No. 308,032, dated November 11, 1884.

Application filed April 5, 1884. (No model.)

To all whom it may concern:

Be it known that I, JOSEPH WALTER FLAGG, a citizen of the United States, residing at Worcester, in the county of Worcester and 5 State of Massachusetts, have invented a new and useful Improvement in Automatic Cash-Carriers, of which the following is a specification.

My invention relates to that class of cash-10 carrying systems in which inclined ways or tracks and rolling cash-carriers are used; and it consists in an improved guard for the ways; in delivery-springs attached to the receiving-tracks; in an improved guard and buffer for 15 receiving the carriers at the cashier's desk; in the construction of the rails at the delivery-stations of the outward track; in the construction of intermediate chambers between the graduated openings of the outward track and 20 the delivery-baskets; in the arrangement of the pull-cords upon the baskets to prevent their rocking upon their axes of suspension; in the construction of the elevators and in the mode of hanging the same; in the mode of 25 hanging and adjusting the tracks, and in the construction of the cash-carriers, as hereinafter set forth.

The accompanying drawings illustrate a cash-carrying system embodying the features 30 of my invention, and in which Figure 1 shows a side elevation of an inward and outward track. Fig. 2 illustrates the mode of hanging and adjusting the tracks. Figs. 3 and 4 show rear and side views of the elevator; Fig. 35 5, the pulleys, b' , forming a portion of the tackle by which the elevator is operated. Fig. 6 is a sectional view of the winding-drum; Fig. 7, a sectional view of the elevated receiving-track; Fig. 8, a sectional view of the main 40 outward track, showing the sliding bar forming the gate of the intermediate chamber. Fig. 9 represents a top view of the inward track; Fig. 10, a top view of the outward track. Fig. 11 is a section of one of the rails 45 of the outward track, showing its construction at one of the delivering-stations. Fig. 12 is a top view of a portion of the outward track having a branch track, and showing the switch employed upon the outward tracks 50 having divergent branches. Fig. 13 is a sectional view of the same on line X X, Fig. 12. Fig. 14 is a toy view of a portion of an in-

ward track having a convergent branch, showing the rigid frog with an inclined surface. Fig. 15 is a side view of the same, with the 55 rail nearest the behold r removed. Fig. 16 is a sectional view on line S S, Fig. 14. Fig. 17 is a sectional view of one of the cash-carriers. Figs. 18 and 19 are plan views of the two hemispheres forming the carrier. Fig. 60 20 is a sectional view of one of the tubes used in the carrier; and Fig. 21 is a side elevation of section of the outward track, having a divergent branch, and showing a side view of the switch, further illustrated in Figs. 12 and 13. 65

Similar letters refer to similar parts in the several views.

In Fig. 1, A indicates an inward track inclined toward the cashier's desk. The cash is transmitted in hollow balls, which roll 7c along the inclined way, and are returned to the salesman upon the oppositely-inclined way or track B. These rolling cash-carriers C are raised from the salesman to the inward track, A, by the elevator D, sliding between 75 suitable vertical guiding-rods. The elevator is raised by pulling upon the cord a , and in order to allow a single short and convenient motion of the cord a to raise the elevator the entire height usually necessary in stores, I 80 carry a cord, d' , from the top of the elevator over a single pulley, b , attached to the ceiling of the room; thence around one of the two pulleys b' shown in Fig. 5; then over the single pulley b' ; then around the second of the 85 two pulleys b' , and then to an eyebolt, b^3 , to which the end of the cord is fastened.

To the strap or block b^4 , holding the two pulleys b' , is attached the pull-cord a . Whatever distance the block b^4 may be lowered by 90 the cord a , the four cords between the block b^4 and the ceiling must each be lengthened the same distance, and the elevator be raised a space equal to four times the motion of the cord a . The cash-carrier rests upon the tilting shelf d , and against the back d' , which I make in the form of a finger, extending from the bottom of the elevator upward high enough to retain the carrier. The finger d' allows the carriers to be placed in the elevator more conveniently, the space at the sides of the finger affording room for the thumb and fingers and permitting the carrier to be retained in the grasp until the carrier rests upon the tilting 95 100 shelf d .

shelf. As the elevator D is raised, the hood or prong d^3 on the tilting shelf strikes the tripping-bar d^4 at the end of the receiving-track A', tilting the shelf d and discharging the carrier C on the track A'. The force with which the elevator is raised in common use causes the shelf d to strike the bottom of the elevator with an injurious blow. To obviate this I place the rubber block d^5 upon the bottom of the elevator, or it may be attached to the under side of the tilting shelf in proper position to be brought between the impinging surfaces.

Upon the top of the elevator D, I attach the cord d^6 by passing the cord through a short piece of rubber tubing, d^7 , and around a pin, d^8 , in the frame of the elevator, carrying the end of the cord back again through the elastic tube, which securely holds the end of the cord, and also forms an elastic cushion to receive the blow against the ceiling, or a cross-bar or stop attached to the vertical guide-rods, to limit the upward motion of the elevator. After the carrier has been discharged upon the elevated receiving-track, it is prevented from rolling off the sides of the track, or from bounding off the track, by a series of guard-wires, e , arranged at short distances apart, and having their ends attached to the rails forming the track A', the wires being arched over the track high enough to allow the carriers to roll beneath them.

To the rails of the elevated receiving-track A', I attach the blade-springs e' , extending over the main track and forming a part of the receiving-track, and of sufficient strength to partially sustain the carriers, which slightly depress their ends as they roll over them, as indicated by the broken lines e' , Fig. 1. By this means the carriers are lowered nearer the main track before leaving the receiving-track. The inclination of the track A' is also increased at the end by the curvature of the springs, giving an additional impetus to the carriers.

At the end of the inward track, A, at the cashier's desk, I place the U-shaped wire f , held by and sliding in the posts f' f'' , attached to the track. The spiral spring f^3 , between the posts f' and a pin or collar, f^4 , on the wire f , serves to hold the wire f in the position shown, the impact of the carriers against the wire f compressing the springs f^3 . The graduated openings in the outward track, by which the graduated carriers are distributed to the several stations, and which were fully described in Letters Patent No. 274,302, granted to me March 30, 1883, are adapted to and employed in the system forming the subject of my present invention. One of these openings is shown at E, Figs. 1 and 10. In order to allow the carriers, which are too large to fall through the opening at E, to pass the same readily and smoothly, I chamfer the inner corners formed by the inner and upper corners of the rails and the curved surfaces of the opening E, as at g g' , these chamfered sur-

faces forming a continuous way, upon which the carriers may pass over the openings too small to allow their passage through.

Beneath the openings E, I place a cage or chamber, F, attached to the under side of the track, one end of the chamber coming immediately beneath the opening E, and the bottom of the chamber F being so inclined that the carriers falling through the openings E and entering the chamber will roll toward the opposite end, which is closed by the bar h , passing transversely across the end of the chamber and resting in the slot h' , the collars h^{10} preventing the endwise motion of the rod. A basket, G, with an open end, h^7 , is held against the under side of the track by a cord, h^2 , wound around the winding-drums h^3 , attached to the sides of the track, and actuated by the coiled spring h^4 , Fig. 6, one end of which is attached to a fixed spindle, h^5 , and the opposite end to the winding-drum. The prongs h^6 , projecting from the basket G, serve to raise the bar h in the slot h' and allow the carriers to pass through the coincident openings into the basket G, which I make long enough to hold two or more carriers.

It is important that the basket G should be prevented from rocking on its axis of suspension as it is raised and lowered. For this purpose I attach cords h^8 h^9 to the opposite and lower corners of the basket, uniting them in a single cord, h^9 , by which the attendant may draw the basket down to remove the carriers, the strain upon the cords h^8 h^9 , holding the basket from rocking or tipping.

Fig. 2 shows the method of adjusting the height and inclination of the outward and inward tracks, and of securing the rails in the same plane. The rod j depends from the ceiling and carries the yoke j' , attached by a set-screw, j^5 , so it may be adjusted vertically through the ends of the yoke j' and also through the lugs j^6 . Attached to the rails i i' of the upper and lower track are vertical rods j^4 , attached to the yoke and to the rails by set-screws j^5 , j^6 , and j^7 . Either of the rails of the upper and lower track may be raised on the rods j^4 and fastened at any desired height by means of the set-screws; or, when the rails of the upper and lower track are adjusted relatively to each other, the rod j^4 may be raised in the yoke and secured by the set-screw j^5 .

Instead of the rods j and j^4 and yoke j' , rods k may be employed extending from the ceiling down by the side of the tracks through lugs attached to the rails, and having set-screws k^1 and k^2 for the vertical adjustment of each rail.

In case the outward track has diverging branches, as shown in Fig. 12, I use a switch, by which the carriers are directed upon either of the divergent tracks, as may be desired.

At the intersection of the rails l l' , I pivot the switch-rail H, held against one of the rails of the main track by a spring, l^2 . A link, l^3 , connects the switch-rail H with one of the arms of the bell-crank l^4 , pivoted to the oppo-

site rail of the main track. A link, l^5 , connects the outer arm of the bell crank with an arm, l^6 , attached to the lower end of the vertical rotating rod l^7 , held in suitable bearings, l^8 , at the side of the track, and having an arm, l^9 , extending across the track and attached to the vertical rod l^8 at such a height as to allow all carriers designed for the branch track I to pass beneath, while all the carriers rolling over the main track whose height above the track exceeds the height of the arm l^9 will move the arm l^9 to the position shown in Fig. 12 by broken lines, and thereby through the connected intermediate devices throw the switch-rail H across the track, as indicated by broken lines, causing the carrier to roll on to the branch track I'. The lengths and relative positions of the arms l^9 and switch-rail H are such that the carriers shall roll upon the end of the rail H before it leaves the arm l^9 , its action upon the arm l^9 holding the rail H in proper position to deflect the carrier upon the track I'. The spring l^2 reverses the position of the switch-rail and its connected operating devices after the passage of the carrier.

When converging branch tracks are used with the inward track, as shown in Fig. 14, I use a frog, J, rigidly attached to the rails at m. The opposite end, m', of the frog rests upon or may be attached to the cross-tie m''. The upper surface of the frog J forms an inclined way, upon which the carrier rolls, the lower end, m', of the inclined surface being low enough, as shown in Fig. 16, to allow the carrier to rest upon each of the rails m' as it leaves the frog J.

The carrier forming the subject of my present invention is a modification of the carrier described and shown in the Letters Patent No. 277,892, granted to me May 22, 1883, and consists of a ball composed of two hemispheres, K and L, each formed of an outer shell composed of paper-pulp pressed into proper shape.

Recessed in the upper hemisphere, K, is a circular plate, n, suitably secured to the outer shell, and having a central opening provided with a screw-thread, n', to receive the screw-threaded tube n''. Around the outer edge of the plate n is a flange, n'', to support the edges of the outer shell.

In the hemisphere L is a similar circular plate, p, with a central screw-threaded opening, p', to receive the threaded tube p'' and an outer flange, p'', to support the edge of the outer shell. Around the edge of the flange p'' is a lip, p'', under which the spring-catches p'' are hooked, thereby locking the two hemispheres together. By turning one hemisphere upon the other until the spring-catches are brought at the openings p'', the two hemispheres are unlocked.

In the hemisphere K is screwed the tube n'', containing a shorter inner tube, r, across the end of which is stretched the elastic diaphragm r', which is firmly held in place by being pressed between the two tubes n'' and r. In the inner

tube are a series of apertures, r'', at which the elastic diaphragm is, of course, not compressed, and the resistance offered by the thickness of the diaphragm to being drawn across the edges 70 of the apertures r'' holds the diaphragm more firmly in place. The outer tube, n'', extends beyond the diaphragm r', forming a receptacle for the cash, and through that portion r'', extending beyond the diaphragm r', are openings r'', which reduce the weight of the tube, and also allow the free passage of air, as the tube n'' is placed over the tube p'', which is a great advantage, as in practice the tube n'' should fit so accurately over the tube p'' as to 80 prevent the air held in the tube n'' from readily escaping otherwise. The tube p'' has a screw-thread, by which it is held in the central screw-threaded opening in the plate p, and it contains an inner tube, s, with an elastic diaphragm, s', and apertures s'', in the same manner and for the same purpose as the tubes n'' and r already described. The tubes p'' and s enter the tube n'', so as to bring the two elastic diaphragms against each other when the hemispheres are locked together, and so the cash held between them may be maintained in the center of the carrier.

Instead of the intermediate chamber, F, and basket G, held against the track, as shown in 95 Figs. 1 and 10, the basket G may be held against the under side of the chamber F; and the opening allowing the exit of the carriers from the chamber may be through the bottom instead of the end, and the prongs h'' on the 100 basket G may be used to lift a bar, h, extending across the opening, in substantially the same manner as described.

What I claim as my invention, and desire to secure by Letters Patent, is—

1. The combination, with the inclined tracks of a cash-carrying system and carriers adapted to roll thereon, of a series of guard-wires attached at their ends to the tracks, and forming arches extending over said tracks at appropriate distances, as and for the purpose set forth.

2. The combination, with the rails of an elevated receiving-track placed over the main inward track of a cash-carrying system, of springs 115 attached to the rails of the receiving-track, and forming an extension of the same, as and for the purpose set forth.

3. The combination, with the rails of an elevated receiving-track, of blade-springs e', attached to the rails of the said receiving-track, as and for the purpose set forth.

4. The combination, with main inward track of a cash-carrying system, of a U-shaped buffer-wire sliding in supports attached to the 125 track, and a spring, f', resting against one of the supporting-posts, and so acting on said U-shaped wire that its elasticity shall counteract the impacts of the carrier against the buffer-wire, as and for the purpose set forth.

5. The combination, with the main inward track of a cash-carrying system, of a U-shaped

buffer-wire, f , supporting posts f' , f'' , and spiral spring f^3 , acting upon the wire f , as and for the purpose set forth.

6. The combination, with the elevator of a cash-carrying system having a tilting shelf, of an elastic block or spring arranged between the bottom or frame of the elevator and the tilting shelf, as and for the purpose set forth.

7. The combination, with the elevator of a cash-carrying system, of a retaining-finger, d' , as and for the purpose set forth.

8. The combination, with the elevator of a cash-carrying system, of the elevating-tackle, as described, consisting of the elevator-cord d^6 , pull-cord a , pulleys b and b^2 , and eyebolt or hook b^3 , and movable block b^4 , with the pulleys b' , all arranged and operating as and for the purpose set forth.

9. The combination, with the elevator of a cash-carrying system, of the lifting-cord d^6 and elastic ferrule d^7 , inclosing the cord d^6 and securely holding the end of the cord, whereby the cord may be attached to the elevator, as and for the purpose set forth.

25 10. The combination, with an outward track of a cash-carrying system having openings to allow the proper distribution of the carriers and movable delivery-baskets, of intermediate chamber communicating with said openings and baskets, as and for the purpose set forth.

30 11. The combination, with the outward track of a cash-carrying system having openings E , of an intermediate chamber, F , arranged under said openings for the reception of the carriers, and having its bottom inclined toward the opposite end, as and for the purpose set forth.

40 12. The combination, with the outward track of a cash-carrying system having a series of openings to effect the proper distribution of the carriers and movable delivery-baskets, and intermediate chambers communicating with said openings and said delivery-baskets, 45 of a transverse vertically-sliding bar for retaining the carriers in the intermediate chambers, said bar being operated by the movable baskets, so as to allow the carriers to pass from the intermediate chambers into the baskets 50 when the baskets are elevated, as and for the purpose set forth.

55 13. The combination, with an intermediate chamber communicating with the openings of an outward track, and having an opening to allow the exit of the carriers therefrom, of a bar extending transversely across said opening in the chamber and sliding vertically in slots, said bar being operated by the delivery-baskets, substantially as described, whereby the carriers may be retained in or discharged from the intermediate chamber, as desired, as and for the purpose set forth.

60 14. The combination of the chamber F , attached to the outward track of a cash-carrying system, of bar h , held in and sliding vertically in the slot h' , delivery-baskets G , attached

to the winding-drums h^3 , and prongs h^6 , as and for the purpose set forth.

15. The combination, with the outward track of a cash-carrying system, of the fixed spindles h^5 , attached to the track, winding-drums h^3 , actuating-springs h^4 , attached to the winding-drums and to the fixed spindles, and movable delivery-baskets G , connected by cords h^2 with said winding-drums, as and for the purpose set forth.

70 16. The combination, with the delivery-basket suspended by a pair of cords attached to winding-drums on the track, of a pull-cord arranged in triangular form, and attached to 80 said delivery-basket on opposite sides of its axis of suspension, as and for the purpose set forth.

75 17. In a cash-carrying system, the outward distributing-track having one or more circular openings, to allow the proper distribution of the carriers, and having the rails of said outward track chamfered at their inner upper corners adjacent to the circular openings, so as to form a continuous track for the rolling 90 carriers, as and for the purpose set forth.

80 18. The combination, with the rails forming the tracks of a cash-carrying system, and having lugs attached thereto, of a supporting-rod, j , yoke j' , attached to the rod j , and capable 95 of vertical adjustment thereon, and adjusting-rods j^4 , attached to and capable of vertical adjustment in the yoke j' , said rods j^4 passing through the lugs on the rails, said lugs being attached to the rods so as to allow vertical adjustment of the rails on the rods j^4 , and also the vertical adjustment of the entire track by the adjustment of the yoke j' on the rods j , as and for the purpose set forth.

90 19. In a way or track of a cash-carrying system, the combination, with a pivoted switch-rail, of a vertical rotating post, a horizontal arm attached to the post and vertically adjustable thereon, and extending over the track so as to be moved by the passing carriers, connecting mechanism for securing the simultaneous action of the rotating post and the pivoted switch-rail, and a spring to reverse their motion after the passage of a carrier, as and for the purpose set forth.

100 20. In a cash system employing rolling carriers of graduated sizes, the horizontal arm l^8 , journaled at the side of the track, and extending over the track at a proper height to be actuated only by the larger carriers intended 110 for the side or branch track, in combination with connected switching devices for deflecting said larger carriers onto the branch track, as and for the purpose set forth.

110 21. The combination, with an inclined way 125 of a cash-carrying system and graduated carriers adapted to roll thereon, of the vertical rotating spindle l^7 , horizontal arm l^8 , attached to said spindle and adjustable vertically thereon, and extending over the track at proper height to be actuated by carriers of a certain size, arm l^6 on post l^7 , bell-crank l^4 , pivoted 130

switch-rail H, connecting-links l^3 and l^5 , and spring l^2 , so attached to and actuating the switching mechanism as to reverse its motion after the passage of an operating-carrier, as 5 and for the purpose set forth.

22. The combination, with the way of a cash-carrying system with graduated carriers adapted to roll thereon, of a horizontal arm extending over the way and attached to a vertical rotating spindle, said horizontal arm being adjusted vertically relatively to the graduated carriers, so as to be moved only by the larger carriers, and a switch-rail arranged to deflect the carriers upon a branch track, when 15 desired, said switch-rail and vertical rotating post being connected so as to move simultaneously, as and for the purpose set forth.

23. The combination, with the inward track of a cash-carrying system having converging branch tracks, of a rigid frog at the intersecting tracks, said frog having an inclined surface, as described, upon which the carriers roll, thereby sustaining the carriers until the 20 normal width of the main track has been reached, as and for the purpose set forth.

24. In a cash-carrier composed of two hemispheres, K and L, the circular dish-shaped plates recessed in the plane surfaces of one or both hemispheres, the flanged sides supporting the outer shell of the carrier, as and for the purpose set forth.

25. In a cash-carrier composed of two hemispheres, K and L, the circular plates attached to or recessed in the plane surfaces of the carrier having concentric screw-threaded openings and screw-threaded tubes inserted there-

in, with connected devices for holding the cash in the center of the carrier, as and for the purpose set forth.

26. In a cash-carrier composed of two hemispheres, K and L, the circular plate p, recessed in one of said hemispheres and having an inwardly-projecting lip, p^4 , adapted to be engaged by hooks or catches attached to opposite hemisphere, whereby the two hemispheres 45 are locked together, as and for the purpose set forth.

27. In a cash-carrier composed of two halves or hemispheres, each half carrying a cash-holding tube, the tube in one hemisphere overlapping the tube in the opposite hemisphere, the series of apertures in the outer end of the overlapping tube communicating with the cash-holding chamber for the purpose of allowing the passage of air from said chamber when the 50 tubes are placed together, and into said chamber when they are taken apart, as and for the purpose set forth.

28. In a cash-carrier, the combination of the outer tubes, n^2 and p^2 , interior tubes, r and s, and diaphragms r' and s' , extending across the inner ends of the interior tubes and held by being firmly inclosed between the outer and inner tubes, said inner tubes having apertures r^2 and s^2 , to increase the frictional resistance 65 upon the inclosed elastic diaphragm, as and for the purpose set forth.
